UNITED STATES PATENT OFFICE.

GEORGE ADELARD BAUDET, OF NEW YORK, N. Y., ASSIGNOR TO THE BAUDET MANUFACTURING COMPANY, OF WOONSOCKET, RHODE ISLAND, A CORPORATION OF RHODE ISLAND.

DESIGN FOR A COMBINED PRESSURE GAGE AND REGULATOR CASING.

55,500.

Specification for Design.

Patented June 22, 1920.

Application filed January 9, 1920. Serial No. 350,451. Term of patent 14 years.

To all whom it may concern:

Be it known that I, GEORGE A. BAUDET, a citizen of the United States, residing at New York, in the county and State of New York, have invented a new, original, and ornamental Design for Combined Pressure Gage and Regulator Casings, of which the following is a specification, reference being had to the accompanying drawing, forming part thereof, and in which;

Figure 1 is a front elevation of the casing; and,

Fig. 2 is a side view of the same.

I claim:

The ornamental design for a combined pressure gage and regulator casing, as shown.

GEORGE ADELARD BAUDET.
